Primary Examiner — Susan Bennett Hattan*Assistant Examiner* — Marie Fast Horse(74) *Attorney, Agent, or Firm* — Banner & Witcoff, Ltd.(57) **CLAIM**

The ornamental design for a streaming media hub, as shown and described.

DESCRIPTION

FIG. 1 is a front perspective view of a streaming media hub showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom rear perspective view thereof.

The broken lines in the drawings depict parts of the streaming media hub that form no part of the claimed design. The sidewalls of the streaming media hub have the appearance of the gray color metallic sheen finish as shown in FIGS. 1 through 8.

1 Claim, 5 Drawing Sheets(56)
